UNITED STATES PATENT OFFICE

WALTER HAHNEMANN, OF KITZEBERG, NEAR KIEL, GERMANY

ARRANGEMENT FOR DIRECTIONAL TRANSMISSION AND RECEPTION BY MEANS OF ELECTRIC WAVES

Application filed July 28, 1925, Serial No. 46,589, and in Germany August 4, 1924.

The invention relates to a method for directional transmission and reception by means of electric waves which is carried out with several transmitting or receiving antennæ arranged at a predetermined distance from one another, preferably in a straight line.

The object of the invention is to obtain as sharp as possible a directional effect by a plurality of transmitting or receiving antennæ located at definite distances apart from one another given by theory.

Directional antenna arrangements have been used heretofore for wireless telegraphy in which either one antenna or several antennæ are arranged at certain distances from each other. In these prior art arrangements either the number of the antennæ used is too small (for instance only 2) in order to produce a well defined directional effect, or else the distances between the antennæ proposed as advantageous are incorrect in fact, in so far as these prior art arrangements propose for different numbers of antennæ used always the same distance. Furthermore, in these prior art devices the directional effect is not variable, in such arrangements, for instance, in which only a transmitting and receiving antenna proper is used and in which for producing the directional effect a stationary screen made of wire is used.

In contradistinction to and as an improvement over these prior art devices, I have found that when the number of antennæ which serve as transmitting and receiving antennæ proper, is increased, the distance of these antennæ from each other must be made dependent upon the number of the antennæ used in order to obtain an optimum directional effect, this variable distance d between the antennæ following the law:

$$d = \frac{n-1}{n} \lambda$$

wherein n denotes the number of antennæ, λ the wave length of the signals transmitted or received.

The method according to the invention consists in using more than two or three, in other words a multiplicity of transmitting or re-

ceiving antennæ which are arranged preferably in a straight line and are located at a distance d from one another which is of the order of magnitude

$$d = \frac{n-1}{n} \lambda$$

in which λ is the wave-length and n the number of antennæ.

For the general formula

$$d = \frac{k}{n} \lambda$$

theory shows that k in this formula should not be much different from $n-1$ if the requirement of as sharp as possible a directional effect of the arrangement is to be obtained. If k is greater than $n-1$, that is to say, if k is approximately equal to or even greater than n , then the auxiliary maxima arising may become predominant, the directional action thereby suffers; if the spacing apart with reference to λ is too small, that is to say, if k is smaller than $n-1$, the directional effect is lost owing to the individual transmitting or receiving points being located within too small a range in relation to the wave-length.

The above will be readily understood from the Figures 1 to 5 of the drawing. In these figures the curves for the plane directional vectors for antennæ arrangements are given for different values of n and k . The vector represents the amplitudes, the energy is therefore proportional to the square of these vectors. The dotted straight line $a-b$ indicates the line on which the different antennæ are mounted.

Another object of the invention consists in producing a sharp directional effect in emitting electrical waves by producing the proper adjustment of time between the particular waves or impulses in the antennæ and in producing the same directional effect in receiving electrical waves in the observer's station by means of time lag circuits inserted between the different antennæ and the source of electrical energy or the observer's station. Instead of making use of time lag circuits the same effect may be obtained by producing the proper relation of phase of the feeding cur-

rent for the particular antennæ in the source of the current itself.

Another feature of the invention consists in shadowing away or reflecting and making use of one of the two rays of waves emitted by an arrangement according to the invention, or by a similar directional arrangement.

The particular features of the invention and some diagrams elucidating some theoretical points are shown in the drawings which represents in :

Figs. 1-5 different diagrams showing up the influence of the number of antennæ and the distance between them,

Fig. 6 an arrangement of antennæ according to the invention together with the particular receiving or transmitting house, more clearly elucidated in the auxiliary Figs. 6a-c,

Figs. 7 and 8 a diagrammatic view of an arrangement of antennæ according to the invention and of the effect of such an arrangement without and with a reflecting screen,

Fig. 9 and 11 side elevations and

Fig. 10 a plan view of screen arrangements for unidirectional reception or transmission,

Figs. 12 and 13 combinations of screens and antennæ.

In Figure 1, the case is shown of two antennæ in the optimum case of $k=n-1=1$. The directional action is still quite weak.

In Figure 2, a case of the invention is given where $n=3$, $k=n-1=2$. The directional effect is already much better than in Figure 1.

Laterally to the direction of the main action, an auxiliary maximum of slight intensity occurs (about one tenth the energy of the main direction).

In Figure 3, $n=3$ and $k=3$, that is chosen too large. Clearly the one auxiliary maximum has swollen to the value of the main maximum. The directional effect is therefore spoiled.

In Figure 4, $n=3$ and $k=1$, that is chosen too small. The good directional action has been lost, the curve does not differ from Figure 1, which is the arrangement with two antennæ.

In order to show what influence the increase in the number of antennæ has, Figure 5 is given. Here the number n of the antennæ is 5 and according to the invention $k=n-1$ is chosen as 4. It is seen how much with five antennæ compared with three antennæ (Figure 2) the sharpness of the directional action has been increased. It shows in this case that a compromise will be possible according to the prevailing practical conditions between the number of antennæ and the sharpness of direction.

The figures are based for the case of transmission on excitation of the individual antennæ in the same phase. Here they give the root of the ratio of the amounts of energy radiated dependent upon the angle to the base

of the arrangement; in the case of reception they give the root of the ratio of the received energy of the total arrangement dependent upon the angle of its base to the direction of the incoming field of electric waves.

If the different transmitting or receiving points are excited at the same time or in the same phase, this means that the maximum directional action is at right angles to their connecting line.

The invention gains a general practical importance particularly by the additional fact that the maximum directional vector according to the invention is made rotatable. This means may be applied according to the invention not only in cases of the before described kind but also for all kinds of antennæ arrangements in which the antennæ are placed at a definite distance from one another and a directional effect is to be produced by means of time or phase displacement of the waves and impulses in the antennæ.

The relation of the vector of maximum emission or reception is attained by an arrangement which permits for the different antennæ points such mutual time displacements of the oscillation phenomenon to take place as are necessary in order to bring the main directional action into the desired angle to the base.

A suitable means for carrying out this feature of the invention consists in the use of time lag circuits, for instance in the form of electric filter chains, whose adjustment as regards their individual links is given on the one hand by the highest employed frequency of electric oscillations and on the other hand by the desired sharpness of graduation of the circular field to be acted upon.

Whilst with the use of time lag circuits the correct phase relation in the antennæ is effected by adjustment of the relative time of travel of the waves in the leads to the individual antennæ, it is possible, of course also, omitting time lag circuits, to produce the phase relation in the antennæ by adjusting beforehand at the source of the current the correct phase relation for the individual antennæ.

This can be achieved in a great many different ways, for example, by relative shifting of the stator of the main frequency machine, by arrangement of rotating fields with stationary windings in which coils are rotatable or by the connecting-in of self-induction coils, condensers and resistances or a combination of the same.

A practical application of the invention arises, for example, when it is a matter of saving as much energy as possible, for example, when the international wireless traffic and communication is to be established for the time being only with one station in a perfectly definite known direction with as little cost as possible and excluding as far as possible interferences with other stations (transmission) or by other stations (reception).

The invention can, however, perform valuable services for other purposes, for example, that of direction determination. In order to avoid in this case the occurrence of confusion with regard to direction owing to sharply prominent auxiliary maxima, in the adjusting of the distances apart of the different antennæ, a small amount of deviation from the theoretically calculated distances d —and a somewhat different deviation with each distance—is made, whereby the auxiliary maxima are obliterated.

Naturally time lag circuits for the rotation of the maximum directional vector have to be variable or adjustable whilst time lag circuits for producing a fixed time or phase relation, for instance for the purpose of balancing differences in the length of the conductors between the antennæ and the source of energy have to be fixed beforehand.

In carrying out the invention all antennæ may be connected to the same transmitting device or to the same receiving device, in circuit with the above described time lag circuits or phase shifting means. In many cases where the desired direction is fixed these time lag circuits or the like can be omitted; also in the case where rotation of the complete antennæ structure is possible, for example, in the case of very short electric wave lengths.

A constructional example of the subject matter of the invention is represented in Figures 6 and 6^a in which four antennæ 1, 2, 3, 4 are chosen and the transmitting or receiving house 9 is assumed to be in the centre of the base out to the side. For the purpose of obtaining as symmetrical an arrangement as possible, the antennæ 1 to 4 are connected in pairs with the transmitting or receiving house by conductor wires 5, 6, 7, 8 as nearly symmetrical and of equal length as possible, the leads for the antennæ 1 and 2 or 3 and 4 respectively which are laid together being arranged so as to be mutually free from induction. The length and the character of all four lines and thus the time difference between the electric oscillations in the station and on the antennæ should be made as far as possible equal; in so far as this is not attained the filter chains represented in Fig. 6^a can be used for correction and equalization in the station house or for equalization at another point of the installation or particular additional links 10 may be inserted in the connecting lines. In the station house (Figure 6^a) between the source of power 15 or the observer's station 16 and the individual leads 5 to 8 to the different antennæ points, electric filter chain compensators 11 to 14 are connected, which are preferably made variable, so that the desired maximum directional action can be selected at will. The variability of the time lag circuits 11—14 is obtained by these circuits being composed of individual links consisting of inductances and condens-

ers, of which links as many can be connected to the corresponding pairs of conductors 5—8 as required. In the example of Fig. 6^a the time lag circuits are shown as built up of equal chains and the connections are so that for each following pair of conductors 5, 6; 7, 8 a gradually increasing number of links has to be cut in. In practice the links of the different chains will not have to be equal but each chain might be built up of the same number of links each link being of gradually increasing value as diagrammatically shown in Fig. 6^b. If alternating currents or waves of pure sinusoidal form are to be transferred to or from the antennæ arrangement a simpler kind of compensator may be applied, as diagrammatically shown in Fig. 6^c, comprising shorter chains of equal links each chain having a phase retarding value of not more than one cycle, and the connections with the conductor pairs being so arranged that only the phase shifting values and not at the same time the time retarding values of the portions of the chains cut in follow gradually each other. In Fig. 6^c for instance the case is given of a phase difference in three antennæ of 2/3 cycles. Accordingly the positions of the sliding contacts 35 and 36, 37 and 38, 39 and 40 respectively are at the beginning of chain 11, after two thirds of chain 12 and after one third of chain 13.

Instead of this means other expedients for phase displacement, such as are for example above described, may be used.

In many cases it will be the fault of the described arrangement that the main directional effect occurs towards two sides displaced from one another at 90° and forming equal angles with the line in which the antennæ are arranged. Then the arrangement for this purpose can according to the invention be improved by cancelling the action towards the undesired side of the main directional vector by screening means itself known. Preferably these screening means are built up and arranged with relation to the main antennæ arrangement so, that one of the said two main directional vectors is as completely as possible deflected towards the same direction as the other. This is an important additional feature of the invention.

Arrangements of reflecting systems of conductors surrounding the emitting or receiving antennæ are known, but only of the kind by which a fixed and not movable directional vector can be obtained. By the particular relative position of the reflecting conductors and the main antennæ arrangement according to the invention the advantage is obtained that both the main directional vector and the reflected vector can be turned completely over almost 180 degrees without any motion of conductors in the field.

Reflecting conductor systems may be built up in numerous variations some of which are

shown in the drawing (Figs. 6 and 9 to 13). Beginning with a directional antennæ arrangement without screen this object of the invention is fully described in the following.

In Figure 7 a plurality of antennæ displaced from one another at definite distances is shown, for instance the five antennæ 15—19 (corresponding to 5—6 of Fig. 6) the direction effect of which may be represented by the arrows a , b , c respectively. To each of these vectors a , b , c there belongs a corresponding reverse vector represented in Fig. 7 by the dotted arrows a_1 , b_1 , c_1 .

Figure 8 shows an example in which way according to the invention the undesired influence of one of each two corresponding directional vectors may be made ineffective. This effect is obtained by means of a screen 20 of such character that the undesired vector—according to the well known rule: angle of incidence equal to angle of deflection—is reflected towards the same direction as the desired maximum vector of direction, as shown by particular position of the arrows a , a_1 , b , b_1 , c , c_1 to one another.

A screen arrangement adapted for this effect is shown in Fig. 9 and 10. The screen consists of a conducting wall comprising perpendicular suspended conductors preferably connected to the earth, the thickness of the screen arrangement amounting to about one wave-length (at least one half wave-length) of the oscillations used. The conducting wall contains a number of lines of conductors (20—24) displaced from one another some metres. The individual conductors preferably are so arranged, as shown in Fig. 10, that the conductors of two neighbouring lines are displaced like the fields of a chessboard. The whole system of conductors is held by the four posts 25—28. The carrying into effect of the invention is not at all questionable for fear of too large dimensions of such an arrangement because nowadays preferably also for large distances use is made of short wave-lengths.

The described screen arrangement acts substantially as a reflector. It may also be built up of conductors consisting of tuned electrical circuits arranged as is shown in Figs. 9 and 10. These tuned circuits have to be damped substantially by radiation for the purpose of re-emitting a substantial part of the impinging energy and of absorbing only a small part. An example of such an arrangement is shown in Fig. 11. It differs from the reflector of Figs. 9 and 10 especially by the variable inductances 25 which are inserted in the perpendicular suspended conductors 20—24. Besides the lines of conductors in this case preferably are positioned from one another at a distance amounting to about one wave-length (at least one half wave-length) of the electrical wave used.

It should be understood that screen ar-

rangements of the described kind (Figs. 9—11) act not only as reflectors but that they absorb also a portion of the impinging energy; this effect is not at all a disadvantage because it is also of importance to dispense of radiotelegraphic effect towards undesired directions and to avoid in this way as far as possible disturbances of the radiotelegraphic communication.

In particular cases it may be advantageous to make use of screen arrangements, and perhaps also of main emitting and receiving arrangements, of a curved form for instance in case of stations where a preferred direction of communication exists.

In Fig. 12 and 13 arrangements of screens of bilateral effect are shown.

Fig. 12 for instance shows two antennæ arrangements A and B parallel to one another and adapted to be cut in at will and separated from one another by a conducting wall C. Each antennæ arrangement comprises five antennæ 15—19 respectively 15'—19'. The right or the left antennæ have to be cut in if in the right or the left semi-circle respectively radiotelegraphic communication is to be effected.

A special advantage of this arrangement consists in the possibility to use both antennæ arrangements at the same time for different communications without disturbing one by the other.

In Fig. 13 an example of the invention is shown in which a main antennæ arrangement D is positioned between two screen arrangements E and F (see also Fig. 6). In this case the screen arrangements have to be cut in alternatively.

In consequence of the fact, that it is possible with the help of arrangements according to the invention to produce with simple means a sharply defined and directed ray of waves, besides the possibility of saving energy and avoiding disturbances between different stations the additional advantage is obtained that the very objectionable interference effects to be observed especially in connection with short waves may be remarkably diminished by the cooperation at one receiving point of different beams travelling over different paths.

If a sufficiently short wave-length is used the whole directional antennæ arrangement may be built up as a rotatable unit (instead of turning the directional vector by means of time lag circuits). This case is especially advantageous because in all directions use can be made of the vector at right angles to the line of the antennæ arrangement, this vector having the highest degree of sharpness compared with all other vectors oblique to this line.

As said already before the deflection of one of the two possible corresponding vectors may be used with advantage in connection

with all kinds of bilateral antennæ arrangements and combinations, i. e. of arrangements which are adapted to emit two beams of waves towards both directions of the antennæ arrangement itself, and in which these two 5 beams have the characteristic feature that in turning one of them the other is turned in the opposite direction. This part of the invention is not limited to the antenna arrangement built up according to the equation mentioned 10 in the introduction of this specification but it may be applied to all kinds of bilateral acting antenna arrangements for emission and reception of electrical waves, the directional effect of which is based upon 15 particular time or phase relations of the waves or impulses in the antennæ of the arrangement.

I claim:—

1. An arrangement for directional radio 20 communication comprising a multiplicity n of more than three antennæ mounted at distances from one another each of the said distances being approximately equal to the value 25 $\frac{n-1}{n} \cdot \lambda$ in which λ is the length of the wave employed for signalling.

2. An arrangement for directional radio 30 communication comprising a multiplicity n of more than three antennæ mounted in a straight line at distances from one another each of the said distances being approximately equal to the value $\frac{n-1}{n} \cdot \lambda$ in which λ 35 is the length of the wave employed for signalling.

3. An arrangement for directional radio 40 communication comprising a multiplicity n of more than three antennæ tuned to a frequency corresponding to a wave-length λ and mounted in a straight line and at distances from one another each of the said distances being approximately equal to the 45 value $\frac{n-1}{n} \cdot \lambda$.

4. In combination an arrangement for directional radio communication comprising a multiplicity n of more than three antennæ 50 mounted at distances from one another; each of the said distances being approximately equal to the value $\frac{n-1}{n} \cdot \lambda$ in which λ is the

length of the wave employed for signalling; 55 an arrangement for shifting the vector of maximum effect.

5. In combination an arrangement for directional radio communication comprising a multiplicity n of more than three antennæ 60 mounted at equal distances from one another; each of the said distances being approximately 65 equal to the value $\frac{n-1}{n} \cdot \lambda$ in which λ is the length of the wave employed for signalling;

an arrangement for shifting the vector of maximum effect comprising means for adjusting individual time intervals of equal value between the individual impulses in the different antennæ for each individual direction of the maximum vector of intensity. 70

6. In combination an arrangement for directional radio communication comprising a multiplicity n of more than three antennæ mounted at equal distances from one another; 75 each of the said distances being approximate-

ly equal to the value $\frac{n-1}{n} \cdot \lambda$ in which λ is the length of the wave employed for signalling; an operator's station; and an arrangement inserted between the said antennæ arrangement and the said operator's station comprising means for adjusting individual time intervals of equal value between the individual impulses travelling in the conductors connecting the antenna arrangement and the operator's station for each individual direction of the maximum vector intensity. 80

7. In combination an arrangement for directional radio communication comprising a 90 multiplicity n of more than three antennæ mounted at equal distances from one another; each of the said distances being approxi-

ately equal to the value $\frac{n-1}{n} \cdot \lambda$ in 95

which λ is the length of the wave employed for signalling; an operator's station; and a compensating arrangement inserted between the said antennæ arrangement and the said operator's station; the compensating arrangement consisting of subdivided and adjustable electrical time lag circuits in combination with a switching device for connecting at will a number of subdivisions of the said time lag circuits into the conducting leads between the antenna arrangement and the operator's station, the different numbers of subdivisions connected into the several time lag circuits constituting multiples of the smallest number of sub-divisions connected into any one time lag circuit. 100

8. In combination an arrangement for directional radio communication comprising a multiplicity n of more than three antennæ mounted at equal distances from one another; 115 each of the said distances being approximate-

ly equal to the value $\frac{n-1}{n} \cdot \lambda$ in which λ is the

length of the wave employed for signalling; an operator's station; and a compensating arrangement inserted between the said antenna arrangement and the said operator's station;

the compensating arrangement consisting of subdivided and adjustable electrical time lag circuits in combination with a switching device for connecting at will a number of subdivisions of the said time lag circuits into the conducting leads between the antenna arrangement and the operator's station; each of the said subdivisions consist-

ing of inductance in series and capacity in shunt, the different numbers of sub-divisions connected into the several time lag circuits constituting multiples of the smallest number of sub-divisions connected into any one time lag circuit.

9. In the combination according to claim 7 a compensating arrangement comprising electrical time lag circuits of equal size subdivided into equal portions in connection with a switching device adapted to adjust equal phase differences between the individual waves in the different antennæ, the different numbers of sub-divisions connected into the several time lag circuits constituting multiples of the smallest number of sub-divisions connected into any one time lag circuit.

10. In an arrangement for directional radio communication the combination with an antenna arrangement comprising at least three antennæ positioned in an approximately straight line and at equal distances from one another; of a reflecting screen built up of electrical conductors and arranged at one side of the said antenna arrangement and in parallel to the row of main antennæ; and an operator's station connected to the said antenna arrangement.

11. In an arrangement for directional radio communication the combination with a main antenna arrangement comprising at least three antennæ tuned to a given frequency and positioned in an approximately straight line and at equal distances from one another; of a reflecting screen built up of a plurality of antennæ tuned to the same frequency and arranged at one side of the said antenna arrangement and in parallel to the row of main antennæ; and an operator's station connected to the said main antenna arrangement.

12. In an arrangement for directional radio communication the combination with an antenna arrangement comprising a multiplicity of antennæ tuned to a given frequency and positioned in an approximately straight line and at equal distances from one another; of a reflecting screen arranged at one side of the antenna arrangement and built up of a plurality of suspended conductors with inductance coils in series arranged in parallel to the row of main antennæ, the said conductors with the said coils being tuned to the same frequency; and an operator's station connected to the said antenna arrangement.

13. In an arrangement for directional radio communication the combination with an antenna arrangement according to claim 1; of a reflecting screen arranged at one side of the said antenna arrangement and substantially in parallel thereto; and an operator's station connected to the said antenna arrangement.

14. In an arrangement for directional radio communication the combination with an

antenna arrangement according to claim 1; of means for shifting the main directional vectors of the said antenna arrangement; and of means reflecting one of the two directional vectors towards the direction of the other; and an operator's station connected to the said antenna arrangement and the said shifting means.

15. In an arrangement for directional radio communication the combination with an antenna arrangement for bilateral directional emission and reception of waves; comprising at least three substantially perpendicular antennæ disposed in an approximately straight line and being tuned to a given frequency; of a reflecting screen built up of a plurality of substantially perpendicular conductors arranged at one side of the said antenna arrangement and substantially in parallel thereto; the thickness of the said screen being approximately equal to the wave-length of the wave corresponding to the natural frequency of the antennæ of the main antenna arrangement and at least one half of this wave-length; and of an operator's station connected to the said antenna arrangement.

16. In an arrangement for directional radio communication the combination with an antenna arrangement for bilateral directional emission and reception of waves comprising at least three substantially perpendicular antennæ tuned to a given frequency and positioned in a substantially straight line and at equal distances from one another; of a reflecting screen built up of a plurality of substantially perpendicular antennæ, arranged substantially in parallel to the main antennæ said perpendicular antennæ being tuned to the same frequency and positioned at distances from one another equal to at least one half of the wave-length of the natural frequency of the said antennæ; and of an operator's station connected to the said antenna arrangement.

17. In an arrangement for directional radio communication the combination with a main antenna arrangement according to claim 1, each of the individual antennæ of this arrangement being substantially perpendicular and tuned to a given frequency; of an operator's station; of a compensating means inserted between the main antenna arrangement and the operator's station and consisting of a number of time lag circuits individually coordinated to the individual antennæ of the said main arrangement and built up of sub-divisions; of a switching device for cutting in at will a number of sub-divisions of each time lag circuit between the operator's station and the corresponding antenna; and of an auxiliary antenna arrangement positioned spacially substantially in parallel to the main antenna arrangement, each of the antennæ of the auxiliary arrangement being tuned to the same natural frequency as the

antennæ of the main arrangement and the distance between the individual antennæ of the auxiliary arrangement being substantially equal to the wave length of the said natural frequency of the antennæ and at least equal one half of this wave-length.

18. In an arrangement for directional radio communication, two bilateral directional antenna arrangements according to claim 1,
10 a reflecting screen for rendering said bilateral arrangements unilateral, said antenna arrangements being positioned at both sides of said screen, an operator's station and means for energizing said antenna arrangements individually at desired time periods.
